Assign to

DES. 2463

Thomas Nills & Son, of same place.

Letters Patent No. 2463. Dated Sept. 25. 1866.

Design for a Candy Figure.

The Schedule referred to in the Letters Patent and making part of the same.

To all whom it may concern:

Be it known that A. Seehardt & Schultze of the City of Philadelphia in the State of Pennsylvania have invented and designed a new Figure for castings in Candy, of which the following is a full and exact description, reference being had to the accompanying photograph (being part of this Specification).

The Design relates to that class of Figures which are cast hollow, of transparent, or opaque Candy and are extensively used as toys for ornamenting Children's trees &c. They are made by pouring the heated liquid Candy into a metallic mould, after that portion of the Candy, which comes in contact with the mould has crystallized and hardened to form a shell of sufficient strength, the remainder of the liquid is poured out again, and the hollow casting is then removed from the mould which to this end is arranged to separate in two or more parts.

The Figure represents a locomotive, the general shape and details of configuration being fully shown in the accompanying photograph.

What I claim as my invention and distinct from the Letters Patent is the Design for a Candy Figure herein set forth.
